FUEL BURNER

Thomas E. Wood, Library, Pa.

Application May 9, 1936, Serial No. 78,837

10 Claims. (Cl. 158—110)

This invention relates to gaseous fuel burners of the type adapted to selectively develop desirable flame characteristics, and it is among the objects thereof to provide a burner which shall be provided with means for regulating the application of the air supply to achieve both a proper premix character of flame and permit control of the flame characteristic as to luminosity and length.

These and other objects of the invention will become more apparent from a consideration of the accompanying drawing constituting a part hereof in which like reference characters designate like parts and in which:

Fig. 1 is a view partially in section and partially in elevation of a burner embodying the principles of this invention; and

Fig. 2 a transverse section taken along the line 2—2, Fig. 1.

In the drawing, the numeral 1 designates a burner housing having a terminal flange 2 abutting against a furnace wall 3 and having an annular housing portion 4 integrally formed to provide an annular chamber 5 with an extension of the housing wall 1. The wall 4 is provided with threaded opening 6 for connection to a threaded conduit or pipe leading to a source of air under pressure. The housing 4 is further provided with a threaded opening 7 in the end wall thereof for receiving a flanged screw sleeve 8, the threads of which coact with the thread 7 of the housing, and the flange of which is provided with a knurled periphery 9 to form a grip by which the member 8 is turnable in its threaded mounting. A gas or fuel nozzle 10 is provided with a threaded surface 11 that coacts with threads formed in the screw sleeve 8, the nozzle 10 being provided with a constricted end 12, which is screw threaded to receive interchangeable tips 13 and with a threaded opening 10a for connection with a fuel line.

A pair of partition sleeves 14 and 15 are disposed within the inner wall 1 of the burner housing to provide a cylindrical and annular burner passage, the sleeve 15 being secured against movement in the housing 1 and the sleeve 14 being telescopingly mounted in a recess 16 of sleeve 15. Sleeve 14 is flared to form a flange or partition 17 to which are secured adjusting rods 18 that extend through perforations in screw sleeve 8, the rods 18 having screw threaded ends for thumb nuts 19 that rest against the outer face of screw sleeve 8. Adjustment of the thumb nuts 19 moves sleeve 14 axially and varies the openings or ports

20 and 21 constituted by the space between parti-

tion 17 of sleeve 14, the inner face of the screw sleeve 8 and the end face of the downwardly flaring inner wall 1 of the burner housing. The numerals 22 and 23 designate the inner and outer burner passages, respectively, that terminate in the burner port 24 of the furnace wall 3.

The operation of the above described burner is briefly as follows: The threaded opening 6 is connected to a source of air under pressure for supporting combustion. The threaded opening 10a of the gas nozzle 10 is connected to a conduit leading to a source of gaseous or liquid fuel. The control of the fuel and air supply is effected by suitable valves in the supply lines or by regulators well-known in the art, and which constitute no part of this invention. It is to be noted that no provision is made for inspirated air as there is no opening on the front side of the burner housing except that of the nozzle 10 connected to the fuel line. Consequently, the total air supply is from air chamber 5 through ports 20 and 21 and by turning thumb nuts 19, the gap or space of the port 21 may be varied to regulate the amount of air that is premixed with the fuel in the passage 22 of the burner. This adjustment will also regulate the size of port 20 through which air passes around the outside of sleeves 14 and 15 in the annular chamber 23, the volume of air supplied to the latter chamber controlling the flame characteristics developed within the furnace chamber.

The outstanding feature of the hereinbefore described burner is the ability to control the air both simultaneously with the regulation of the air supplied to the inner burner passage or independently thereof. Thus by adjusting thumb nuts 19, both ports 20 and 21 are simultaneously adjusted, the one increasing while the other decreases and vice versa, depending on the direction in which the thumb nuts 19 are turned. Once the desired premix is obtained in the inner passage 22 by regulation of port 21, adjustment of the port 20 can be made without disturbing port 21 to passages 22 and 23 by turning the screw sleeve 8, which effects axial movement of the entire assembly of parts, including sleeve 14, in an axial direction to vary the size or degree of opening of the port 20, thereby varying the volume of air in the passage 23 without varying the air within the passage 22.

By means of the foregoing simple adjustments of the air supply ports, any desirable burner or flame characteristic is obtainable within the limits of fuel and air supply to and within the capacity of the burner.

While I am aware that it has been heretofore

proposed to provide burners with controls to vary the so-called primary and secondary air supply, none of these, to my knowledge, provide for both simultaneous and individual adjustment 5 of the air supply passages as herein provided. In terms of burner characteristics, the primary object of regulating the air ports is to obtain a neutral flame condition for efficient burning of the fuel. By adjusting the sleeve 8 to control 10 the air passage 20 leading to the outer burner passage 23, such a neutral combustion can be obtained by supplying just enough air to support combustion in or beyond the outer passage. By then turning the thumb screw members 19, passage 15 21 may be regulated to obtain desirable flame characteristics. By regulating both passages 20 and 21 in the manner hereinbefore described, neutral, oxidizing or reducing atmospheres may be created in the furnace. Thus, by 20 the simple adjustment herein provided, true proportions of air and fuel for complete combustion are obtainable, as well as insufficient and excess air supply in support of combustion, resulting in reducing or oxidizing atmospheres.

25 Although one embodiment of the invention has been herein illustrated and described, it will be apparent to those skilled in the art that various modifications may be made in the details of construction without departing from the principles 30 herein set forth.

I claim:

1. A gas burner comprising a cylindrical housing having a threaded opening at one end, and a screw threaded sleeve in said opening, said 35 housing having a double wall for a portion of its length forming an annular chamber around an inner chamber, said outer chamber having an inlet for a source of air supply under pressure, and having a passage communicating with the open 40 end of the inner chamber, an annular partition dividing the inner chamber into multiple burner passages, a sleeve coating with the end of the partition and being adjustable for axial movement relative to the partition member, said sleeve 45 having a flanged end disposed in the space between the outer air chamber and the end of the inner housing wall dividing that space into air passages leading into the outer and inner burner passages, the flange of the sleeve being mounted 50 to be movable with the screw threaded sleeve at the end of the burner housing and means for adjusting said flanged sleeve independently of said screw threaded sleeve to vary the gap of 55 said openings.
2. A gas burner comprising a cylindrical housing having a double wall for a portion of its length to form an annular air chamber around an inner chamber, said outer chamber having an inlet connection for a source of air supply, 60 the inner wall of the housing terminating short of the end wall to form a gap between the annular air space and the inner chamber, a cylindrical partition within the inner chamber of the burner dividing the same into a central cylindrical and an outer annular gas and air passage, 65 respectively, a flanged sleeve cooperating with said partition member being slidably mounted for axial movement relative thereto, the flange of the sleeve being disposed in the space between 70 the terminus of the inner burner wall and the end wall of the burner housing dividing said space into ports for the supply of air to the gas and air passages of the burner, a closure at one end of the burner housing, means for adjustably 75 attaching the flanged sleeve to said closure

whereby said sleeve may be axially adjusted to vary the degree of opening leading to the gas and air passages of the burner and said closure being adapted for axial movement independently of said sleeve adjusting means to control the 5 volume of air supply to the annular air passage of the burner.

3. A gas burner comprising a cylindrical housing having a double wall for a portion of its length to form an inner and outer chamber, the 10 inner wall of the housing terminating adjacent the end wall thereof to form an air space of substantial proportion, said housing having an air inlet connection for the outer chamber and a screw threaded opening in the end wall adjacent 15 the end of the inner housing wall, a cylindrical partition dividing the inner burner chamber into a cylindrical and annular burner passage, a flange sleeve coating with the end of said partition to be movable axially thereof, a screw 20 threaded annulus having an outer threaded surface coating with the threads in the opening of the end wall of the burner housing and having a screw threaded opening for receiving a fuel nozzle adapted for connection to a source of fuel 25 supply, adjustable means accessible on the exterior of the threaded sleeve attached to the flange sleeve of the partition member whereby the latter is axially movable to vary the space 30 on both sides of the flange, thereby controlling the volume of air delivered to the cylindrical and annular burner passages, and said screw threaded sleeve being angularly movable to effect axial movement of the flange partition member, thereby varying the gap leading to the annular 35 burner passage without varying the gap leading from the air chamber to the inner cylindrical burner passage.

4. A gas burner comprising a cylindrical housing having a double wall for a portion of its 40 length forming an outer air chamber and an inner burner chamber, the inner wall of the housing tapering inward and forming a gap at the end wall of the housing, said housing having an air inlet in its outer wall and an opening in the 45 end wall adjacent the tapered end of the inner wall, a closure for the end wall adapted to be axially movable relative to the end of the tapered wall and having a fuel nozzle mounted therein, a cylindrical partition disposed within the burner chamber dividing said chamber into a cylindrical and annular passage, said partition being 50 recessed at one end, a flanged sleeve having its end portion disposed in the recess of the partition member to be axially movable therein and having its flanged portion disposed in the gap between the end closure of the burner and the tapered end of the burner wall, said sleeve being 55 adjustably mounted on the end closure member to be axially movable relative thereto, and said sleeve being bodily movable upon axial movement of the end closure member.

5. In a gas burner having a central passage surrounded by an annular passage for directing a gaseous fuel and air to a heating chamber, a 60 fuel supply passage communicating at one end with said central burner passage and an air supply passage adjacent the fuel supply passage and communicating with both the inner and outer burner passages, and adjusting means for subdividing the air passage to control the relative 65 volumes of air supplied to the inner and outer burner passages, said means being further adjustable to vary the air supplied to the outer passage of the burner only.

6. In a fuel burner, a tubular air passage and a tubular burner passage concentric with said air passage in spaced relation therewith, a fuel supply passage communicating at one end with said burner passage, an air supply passage communicating at one end with both said air and burner passages, and means disposed in said air supply passage for simultaneously regulating the relative volume of air supplied to said passages. 5
- 10 7. In a fuel burner, a tubular air passage and a tubular burner passage concentric with said air passage in spaced relation therewith, a fuel supply passage communicating at one end with said burner passage, an air supply passage communicating at one end with both said air and burner passages, and a common valve means for regulating the relative volume of air supplied to said passages. 10
- 15 8. In a fuel burner, a tubular air passage and a tubular burner passage concentric with said air passage in spaced relation therewith, a fuel supply passage communicating at one end with said burner passage, an air supply passage communicating at one end with both said air and burner passages, a partition disposed in said air supply passage dividing the air stream to said air and burner passages, and means for adjusting said partition to vary the division of air to the respective passages. 15
- 20 9. In a fuel burner, a tubular air passage and a tubular burner passage concentric with said air passage in spaced relation therewith, a fuel supply passage communicating at one end with said burner passage, an air supply passage communicating at one end with both said air and burner passages, a partition disposed in said air supply passage dividing the air stream to said air and burner passages, and means for adjusting the partition longitudinally of said air and fuel passages to vary the volume of air supply to the respective passages. 20
- 25 10. In a fuel burner, a tubular air passage and a tubular burner passage concentric with said air passage in spaced relation therewith, a fuel supply passage communicating at one end with said burner passage, an air supply passage communicating at one end with both said air and burner passages, a partition disposed in said air supply passage dividing the air stream to said air and burner passages, means for simultaneously varying the volume of air leading to the air and burner passages, and means for independently varying the volume of air supplied to said air passage. 25
